UNITED STATES PATENT OFFICE.

JOHN SCHUMACHER, OF LOS ANGELES, CALIFORNIA.

PLASTER-BOARD.

1,333,579.

Specification of Letters Patent.

Patented Mar. 9, 1920.

Application filed July 5, 1919. Serial No. 308,765.

To all whom it may concern:

Be it known that I, JOHN SCHUMACHER, a citizen of the United States, residing at Los Angeles, in the county of Los Angeles 5 and State of California, have invented new and useful Improvements in Plaster-Board, of which the following is a specification.

This invention relates to plaster board consisting of a plastic body disposed between fibrous sheets, such as paper, and to 10 which it adheres.

The plastic composition commonly used for plaster board is brittle, after it has hardened, and will break and chip at the edges 15 with rough handling. The finished lengths of plaster board are set up on end during handling and transportation. During such handling the edges are sometimes broken and chipped, the surface sheets broken away 20 from the plaster body, and the board otherwise marred at the edges. When the edges of the board become wet due to lack of protection during damp weather, or during putting, the moisture is absorbed by the plastic 25 causing it to swell slightly and the paper sheets to loosen at the edges.

The principal object of this invention is to provide a plaster board having the exposed edges of the plastic body case-hardened and waterproofed. Thus, swelling by 30 the absorption of moisture, loosening of the paper sheets due to absorption of moisture, and chipping of the edges during handling is prevented.

These objects will be more fully understood, as will also other objects and corresponding accomplishments of my invention, from the following detailed description of a preferred embodiment thereof. For the 40 purpose of this description reference is had to the accompanying drawing, in which:

Figure 1 represents in perspective a fragment of the end of a finished length of plaster board; Fig. 2 is a section through the 45 plaster board at one end, the view being on an enlarged scale; Fig. 3 is a perspective view of fragments of two lengths of plaster board at a seam or joint, illustrating the seam produced with my improved plaster 50 board; and Fig. 4 is a view similar to Fig. 3 showing a seam between lengths of plaster board which are not case-hardened and have swelled due to the absorption of moisture.

The plaster board shown herein is prefer- 55 ably made of plaster placed between sheets of paper which have been treated so as to

retard permeation by moisture. During the process of manufacture the units of plaster board are piled in stacks prior to the setting and are trimmed to the finished length dimensions. The board is permitted to set 60 while in the stack, and later further dried by placing in dry kilns. In the process just described I prefer to angle the stacks of units so that they stand upon their side 65 edges, suitably spaced apart, in which position they are placed in the kiln. During this initial handling, especially when angling the units, the edges may become marred.

The plaster board shown herein has the 70 general appearance of ordinary plaster board and the initial steps in the process of manufacturing are carried out as usual. Referring more particularly to the drawing, the covering sheets of paper are indicated by 75 5 and 6, and the intermediate body or layer of plastic composition by 7.

Immediately after the units have been trimmed, and while in the stack, a sizing or cement glue, for illustration one having the 80 ingredients gelatin glue, alum, and potash, is applied to the exposed edges of the plastic body. This may be done in any manner found convenient as by spraying or painting the edges. However, my invention is 85 not limited to the application of the glue while the board is soft. The application may be made at any time. Sufficient glue should be applied so that the latter will impregnate the plastic body, forming when 90 dry case-hardened edges. Such an edge is indicated by 8 in Figs. 2 and 3. When thoroughly dry the plastic body, at the edges where it has been impregnated, will be case-hardened and water-proof. The edges are 95 thus reinforced and moisture resistant.

Referring to Fig. 4, lengths of plaster board A and B having untreated edges are joined by a plaster putty C. This putty is moist when applied, and the moisture therefrom will permeate the edges of the plaster board lengths at the seam. This results in the edges swelling and forming ridges. As the plaster board is installed in building structures by placing lengths upon the walls 100 and putting the seams, the result will be that objectionable ridges may be formed at the seams. Another objection is that the paper may loosen at the edges and roll or curl. 110

In Fig. 3 I have shown two lengths of plaster board D and E provided with edges

treated according to my invention. The plaster putty F dries and hardens without the moisture permeating the edges of the plaster board lengths at the seams, the glue 5 preventing the same. Thus, a smooth wall is secured.

In the foregoing description, I have described my product as formed by using paper which retards permeation of moisture. However, the invention is not limited 10 to plaster board formed by this process.

What I claim is:

1. A plaster board comprising a plastic body having its edges impregnated with a 15 reinforcing and waterproofing substance.

2. A plaster board comprising a body of plastic material disposed between fibrous covering sheets adhering thereto, the exposed edges of said body being impregnated 20 with a case-hardening and waterproofing substance.

3. A plaster board comprising a body of plastic material, and top and bottom paper covering sheets adhering thereto, the ex-

posed edges of said body being impregnated 25 with a case-hardening and waterproofing substance.

4. A plaster board comprising a body of plastic material disposed between fibrous covering sheets adhering thereto, the ex- 30 posed edges of said body being impregnated with a case-hardening substance.

5. A plaster board comprising a body of plastic material and top and bottom paper covering sheets adhering thereto, the ex- 35 posed edges of said body being impregnated with a reinforcing substance.

6. A plaster board comprising a body of plastic material disposed between fibrous covering sheets adhering thereto, the ex- 40 posed edges of said body having a reinforcing and waterproofing substance applied thereto.

In witness that I claim the foregoing I have hereunto subscribed my name this 26th 45 day of June, 1919.

JOHN SCHUMACHER.
